US00D708735S

(12) **United States Design Patent**
Lang et al.

(10) **Patent No.:** US D708,735 S
(45) **Date of Patent:** ** Jul. 8, 2014

(54) **FRAME FOR BREATHING MASK**

(71) Applicant: **ResMed R&D Germany GmbH**,
Martinsried (DE)

(72) Inventors: **Bernd Lang**, Graefelfing (DE); **Achim Biener**, Aufkirchen (DE)

(73) Assignee: **ResMed R&D Germany GmbH**,
Martinsried (DE)

(**) Term: **14 Years**

(21) Appl. No.: **29/456,114**

(22) Filed: **May 29, 2013**

Related U.S. Application Data

(60) Continuation of application No. 29/347,618, filed on Mar. 16, 2010, now Pat. No. Des. 685,462, which is a continuation of application No. 29/311,143, filed on Dec. 31, 2008, now Pat. No. Des. 614,762, which is a continuation of application No. 29/290,110, filed on Oct. 23, 2007, now Pat. No. Des. 585,982, which is a continuation of application No. 29/239,063, filed on Sep. 27, 2005, now Pat. No. Des. 572,816, which is a division of application No. 29/219,617, filed on Dec. 21, 2004, now Pat. No. Des. 515,698, which is a division of application No. 29/190,511, filed on Sep. 23, 2003, now Pat. No. Des. 502,260, which is a division of application No. 29/163,978, filed on Jul. 17, 2002, now Pat. No. Des. 484,237.

(57) **CLAIM**

The ornamental design for a frame for breathing mask, as shown and described.

DESCRIPTION

FIG. 1 is a front perspective view of a frame for breathing mask showing our new ornamental design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines showing environment or structure of the breathing mask frame are for illustrative purposes only and form no part of the claimed design.

1 Claim, 4 Drawing Sheets
